CLAIM

The ornamental design for a combined beach towel, pillow, pockets, carrying strap, and convertible bag, as shown and described.

DESCRIPTION

FIG. 1 is a front elevational view of a combined beach towel, pillow, pockets, carrying strap, and convertible bag showing our new design;

FIG. 2 is a right side elevational view thereof, the left side being a mirror image;

FIG. 3 is a rear elevational view thereof;

FIG. 4 is a top plan view thereof; and

FIG. 5 is a bottom plan view thereof.

The broken lines shown in FIGS. 1 and 3 are understood to represent conventional stitching.
